UNITED STATES PATENT OFFICE.

WILLIAM T. MERSEREAU, OF ORANGE, NEW JERSEY.

DESIGN FOR METAL STAIR-PLATES.

Specification forming part of Design No. 7,793, dated October 13, 1874; application filed September 9, 1874.
[Term of Patent 7 years.]

To all whom it may concern:

Be it known that I, WILLIAM T. MERSEREAU, of Orange, Essex county, New Jersey, have invented and originated a new and original Design for Metal Stair-Plates, of which the following is a specification:

The nature of my design is fully and clearly shown in the accompanying photographic impression, to which reference is made; and consists in a ground-work formed by a series of inclined lines crossing each other, over which a Grecian border is placed.

I claim—

The design for metal stair-plates, consisting of a ground-work formed of a series of inclined lines crossing each other, over which a Grecian border is placed, as shown.

W. T. MERSEREAU.

In presence of—

A. SIDNEY DOANE,
OBA WOODRUFF.
